UNITED STATES PATENT OFFICE.

ANTONIO BORRÁS AND FERNANDO IRIARTE, OF BUENOS AIRES, ARGENTINA.

AEROPLANE.

1,216,652.

Specification of Letters Patent. Patented Feb. 20, 1917.

Application filed April 8, 1916. Serial No. 89,758.

To all whom it may concern:

Be it known that we, ANTONIO BORRÁS and FERNANDO IRIARTE, citizens of the Republic of Portugal and of Argentina, respectively, and both residents of the city of Buenos Aires, Argentina, have invented certain new and useful Improvements in Aeroplanes, of which the following is a specification.

10 Our invention relates to an improvement in aeroplanes and has as its object the provision of a novel control for the aeroplane rudder whereby a single lever may be actuated to incline the rudder up or down or 15 slanting sidewise in either direction or a combination of such motions. By this means the aeroplane may be directed up or down or to either side, or directed to climb spirally in either a right or a left hand direction 20 or permitted to vol-plane downward in a similar way.

In the following we have described, in connection with the accompanying drawings, a structure illustrating one way of carrying out our invention, the features thereof being more particularly pointed out herein-after in the claims.

In the drawings Figure 1 is a plan view of a mono-plane equipped with a rudder and steering mechanism embodying our invention; Fig. 2 is a detail sectional view, on a slightly larger scale, of the rudder operating means; Fig. 3 is a central vertical sectional view of the rear portion of the structure shown in Fig. 1, parts being broken away; Fig. 4 is a view similar to Fig. 3 but in horizontal section; Fig. 5 is a perspective view of the steering mechanism detached and Figs. 6 and 7 are detail views of parts of 40 the steering mechanism.

Similar numerals of reference indicate similar parts throughout the several views.

1 indicates the body of the aeroplane, which may be made of any suitable light 45 weight material such as aluminum, etc., 2, 2 indicate the wings, 3 indicates the propeller, driven by any suitable means (not shown), 4, 4 indicate the side vanes and 5 indicates the rudder. 6 indicates a rod extending 50 transversely of rudder 5 and rotatably journaled in yoke 7. 8 indicates a shaft journaled in bearings 9 and 10 in body 1 and attached firmly to yoke 7, preferably as shown in Fig. 2, where yoke 7 is shown as provided 55 with a projecting portion 11 over which shaft 8, here shown as hollow, fits and to

which it may be fastened in any convenient way. 12, 12 indicate ball bearings on which yoke 7 turns against bearing 10. 13 indicates a sprocket wheel mounted on the end 60 of shaft 8. 14 indicates the pit of the aeroplane and 15 a seat for the operator. 16 indicates a lever pivoted in strap 17 at 18. 19, 19 indicate hollow trunnions to which strap 17 is firmly attached at each end, the 65 trunnions being rotatably mounted in suitable bearings in opposite sides of the body. 20, 20 indicate auxiliary levers fixedly mounted on trunnions 19, 19. 21 indicates a third auxiliary lever fixedly mounted on 70 rod 6 in the rudder. 22, 22 and 23, 23 respectively indicate connections between the upper ends of levers 20, 20 and the upper end of lever 21 and the lower ends of levers 20, 20 and the lower end of lever 21. 24 indicates a connection, preferably in the form 75 of an endless flexible rope of suitable material, fastened at 25 to lever 16, running through a portion of each of hollow trunnions 19, 19, and thence over guide rollers 80 26, 26 over sprocket 13. 27 indicates a sprocket chain forming a part of rope 24, passing over sprocket wheel 13 and 28 a shield to prevent disengagement of the 85 sprocket chain and wheel.

In operating or directing the rudder a backward and forward movement of lever 16 will cause the rudder, through auxiliary levers 20, 20 and 21 and connections 22 and 23, to be lowered or raised horizontally, lever 21 being fast on rod 6 and rod 6 being rotatably mounted in yoke 7. Point 25, where rope 24 is fastened to lever 16, and point 18 where lever 16 is pivoted to strap 17 being at substantially equal distances from 90 the center of rotation, through trunnions 19, 19 extended, the yoke 7 is not actuated to be turned during the backward and forward motion of lever 16. But if lever 16 is moved from side to side upon its pivotal point 18, then through rope 24 passing over sprocket 13 the rudder is caused to be raised or lowered at its ends according to the motion given to lever 16. It will also be seen 95 that if the lever is moved to either side and then shifted forward or backward, a combination of motions may be given to the rudder. For example, if the lever 16 is shifted backward rudder 5 will be depressed horizontally and the air currents striking 100 110 against the same will cause the aeroplane to descend; if the lever is shifted forward rudder

der 5 will be elevated horizontally and the air currents striking against the same will cause the aeroplane to rise; if the lever is shifted to the left (in the drawing), the lever standing neutral as to rope 24, that is rudder 5 being in a horizontal position, the right hand end of the rudder will be depressed and the aeroplane will turn sidewise to the right; if the lever is however shifted to the right under the conditions last set forth, the left hand end of the rudder will be depressed and the aeroplane will turn sidewise to the left; if the lever 16 be shifted backward and to the left at the same time the rudder will be depressed horizontally and depressed at the right hand end, thus permitting the aeroplane to vol-plane downward circling to the right. If the lever be shifted forward and to the left at the same time, the rudder will be elevated horizontally and depressed at the right hand end and the aeroplane will climb spirally circling to the right. If the lever 16 be shifted backward and to the right at the same time, the rudder will be depressed horizontally and depressed at the left hand end, thus permitting the aeroplane to vol-plane downward circling to the left. If the lever 16 be shifted forward and to the right at the same time, the rudder will be elevated horizontally and depressed at the left hand end and the aeroplane will climb spirally circling to the left.

It is clear that we have provided a rudder control wherein by a shifting of a single control lever, the various motions of the aeroplane may be directed and the aeroplane guided as desired.

The particular construction and arrange-

ment of parts is not essential and we do not restrict ourselves to such further than the scope of the appended claims demands.

We claim:

1. In an aeroplane, a yoke rotatably carried by the aeroplane body, a rod rotatably journaled in the yoke and extending beyond the same at each end, a rudder mounted on said rod, a lever fixedly mounted on the rod and a common operating means for controlling the movement of said yoke and rod, either simultaneously or dissimultaneously.

2. In an aeroplane, a rudder suspended to be free to move up and down and to be tipped sidewise in either direction, a control lever, a strap to which said lever is pivoted, a pair of rotatable trunnions to which the ends of said strap are fixed, auxiliary levers fixedly mounted on the trunnions, an auxiliary lever carried by the rudder, connections between said auxiliary levers on the trunnions and the auxiliary lever on the rudder and an additional connection for sidewise tipping between the control lever and the rudder.

3. In an aeroplane, a yoke rotatably carried by the aeroplane body, a rod rotatably journaled in the yoke and extending beyond the same at each end, a rudder mounted on said rod, an auxiliary lever fixedly mounted on the rod, a control lever and connections actuated by the movement of the control lever to move the yoke and the auxiliary lever either simultaneously or dissimultaneously.

In testimony whereof we have signed this specification.

ANTONIO BORRÁS.
FERNANDO IRIARTE.
